F. D. VAN NORMAN

GRINDING MACHINE

Filed Feb. 20, 1920

4 Sheets-Sheet 2

This technical drawing illustrates a complex mechanical assembly, likely a component of a larger machine. The drawing is labeled 'Fig. 2.' at the top center. The assembly includes several key parts: a large cylindrical component labeled 'R' on the left; a central vertical structure with a slot labeled 'Y'; and a vertical column on the right labeled 'H'. Various other parts are labeled with letters A through Z, including 'A', 'B', 'C', 'D', 'E', 'F', 'G', 'I', 'J', 'K', 'L', 'M', 'N', 'O', 'P', 'Q', 'S', 'T', 'U', 'V', 'W', 'X', 'Y', 'Z', and 'Z1'. The drawing uses lines to represent mechanical connections and components, with some parts shown in cross-section. The style is characteristic of early 20th-century engineering blueprints.

UNITED STATES PATENT OFFICE.

FREDERICK D. VAN NORMAN, OF SPRINGFIELD, MASSACHUSETTS.

GRINDING MACHINE.

Application filed February 20, 1920. Serial No. 360,096.

To all whom it may concern:

Be it known that I, FREDERICK D. VAN NORMAN, a citizen of the United States of America, residing at Springfield, in the county of Hampden and State of Massachusetts, have invented certain new and useful Improvements in Grinding Machines, of which the following is a specification.

10 This invention relates to improvements in grinding machines. The particular embodiment of the invention, chosen for illustrative purposes, is adapted for high speed precision grinding and is of the general type disclosed in U. S. Letters Patent No. 1,303,744, granted May 13, 1919, to Charles E. Van Norman.

The machine disclosed in said patent is characterized by the provision of means whereby the work may be quickly brought into offset relation with the tool for the purpose of testing, measuring, inspecting or removing the work, and whereby the work may be as readily returned to and locked in correct operating relation with the tool. The work-carrying spindle in such machines is mounted for exceedingly free rotation and this, coupled with the considerable speed at which the spindle rotates, 30 means that the work will revolve for a long time even after it is disconnected from its source of power.

An object of this invention is to provide, in a machine of this general class, means which will automatically retard the rotation of the work-carrying spindle when it, and the tool, the one relatively to the other, are brought toward or into offset relation.

Another object of the invention is to provide, in a machine of the general class described, means automatically operable, as the work-carrying and tool-carrying spindles are moved, the one relatively to the other, toward or into offset relation, to disconnect the first-named spindle from its driving means, and other means automatically operable at or about the same time to cause an additional retardation of the first-named spindle.

Another object of the invention is to provide a grinding machine of the general type described, which is entirely self-contained and with which the several overhead belt connections, usually necessary, are eliminated.

Another object is to provide a compact machine, of the general type described, which will occupy a minimum of floor space, and to extend the working range of such machines.

According to the last-named object, separate and longitudinally spaced pedestals are provided, one for the work head and one for the wheel head, and such pedestals are connected together by a common base portion, but at a level which is a substantial distance below the bases of said heads. Such pedestals are so arranged as to afford between them a pronounced gap or depression which underlies both the work and tool in all their various positions and extends so far below their heads that work of widely varying diameter may be handled. By this improvement, I am enabled to obtain a working range at least twice as great as that of any other machine, with which I am familiar, for a given amount of floor space.

Another object of the invention is to provide in a grinding machine, wherein a rotary spindle is carried by a reciprocable slide and wherein the driving means for such spindle is mounted in the supporting frame of the machine, compensating devices associated with the connections between said means and spindle to maintain a uniform driving engagement with the spindle at all points in its range of travel.

A further object of the invention is to provide in a grinding machine having a rotary spindle mounted in a slide which is movable both longitudinally and transversely, a driving means for the spindle mounted in the supporting frame of the machine and compensating devices associated with the connections between said means and spindle to maintain a uniform driving connection therewith at all times and yet permit free movement both longitudinally and transversely.

A further object of the invention is to provide in a grinding machine generally improved mechanical structure.

Other objects and advantages will appear in the following description and in the illustrative embodiment of the invention in the accompanying drawings, in which,—

Fig. 1 is a front elevational view of a machine embodying the invention;

Fig. 2 is a plan view thereof;

Fig. 3 is a diagrammatical plan view illustrative of the driving connections;

Figs. 4 and 5 are elevational views of the left and right hand ends of the machine as viewed in Fig. 1;

Figs. 6 and 7 are longitudinal end cross-sectional views, respectively, of the clutch;

Figs. 8, 9 and 10 are fragmentary sectional views illustrative of various details of the automatic feeding means; and

Fig. 11 is an enlarged fragmentary sectional elevation taken on the line 11-11 of Fig. 2.

Referring to these drawings; the machine includes a main supporting frame which comprises three distinct parts,—viz, two separate and longitudinally spaced pedestals A and B which are connected by a base portion C. The top surface D of the connecting portion C is, however, a substantial distance below the tops of the pedestals A and B and leaves a gap or depression E between them of substantial depth. The adjacent surfaces of the pedestals A and B are preferably vertical, or substantially so, and these surfaces, which form walls of the gap E are extended laterally beyond the pedestals, as indicated at F in Fig. 4 to make the width of the gap at least substantially co-extensive with the travel of the work head which, as will appear, is slidable transversely on pedestal A.

The pedestal B is provided with longitudinally directed ways G (Fig. 5) which slidably support a slide, or carriage H and which extend from one end of the pedestal to the other. It is to be noted particularly that the left face of pedestal B does not project beyond the left end of the ways G, so that a free, unobstructed space is left to permit free movement of the grinding wheel, both longitudinally and crosswise, through the desired ranges, even though the wheel is far greater in size than shown.

The crosswise movement of the wheel, necessary for cross feeding purposes, is accomplished by relatively slow acting means of any suitable character. Thus, the wheel I, which is mounted on a tool carrying spindle J, rotatably mounted in a wheel head or sub-slide K, slidable crosswise on slide H, may be moved by a screw (conventionally indicated at L) in a well-known manner. Screw L may be manually moved by means of the hand wheel M or by any other suitable means, as desired. The cross feeding movement of the wheel may be automatically accomplished, if desired, as disclosed in the aforesaid patent.

The main slide, or carriage H, is longitudinally reciprocable and may be reciprocated by any suitable means. For example, a hand wheel N, rotatably supported in pedestal B, is arranged to turn a gear O, and such gear meshes with a rack P fixed to the

underside of carriage H, all as indicated in Fig. 5. Obviously, any other suitable means may be employed, as desired, for actuating the slide H and the invention is independent of the particular means employed. The slide H may be automatically actuated, as will later appear.

The pedestal A is extended laterally beyond pedestal B and is provided with ways Q which extend in a direction at variance with ways G and usually, although not necessarily, transversely to the latter as shown. The ways Q slidably support a slide R and such slide carries a work head S, which is preferably angularly adjustable on slide R, as indicated, and as more fully disclosed in the aforesaid patent. The work-head S rotatably supports a spindle T which carries at one end a chuck U, or any other suitable work-supporting means. The work is indicated at V.

The slide R is movable by quick-acting means to bring the work V and tool I into offset relation. The means by which this result is accomplished are substantially those of the aforesaid patent and therefore require no extended description here, reference being made to such patent for a more complete disclosure. Briefly, a rack W, fixed to ways Q, is engaged by a gear X which is supported in slide R for rotation about a vertical axis and is movable by a handle Y. Associated with handle Y is a latch Z which cooperates with a shoulder Z' (preferably adjustable as indicated) to hold the work V in operating alignment with the tool I. Although the engagement of the parts Z and Z' hold the slide R from movement only in one direction, additional means like those of the aforesaid patent are employed so that when latch Z engages shoulder Z' the slide R is positively held from movement in either direction.

Obviously, the important result aimed at by the mechanism just described, is the rapid separation of the work and tool and this may be accomplished by moving either relatively to the other. It is not then necessarily essential for all purposes that the work be moved by the quick-acting means as described, although such arrangement is generally preferable.

In connection with the slide R and work-carrying device V, it is to be noted that the right vertical wall of pedestal A does not extend beyond the slide or the device V, thus affording opportunity for the free travel transversely of work-carrying devices of much larger diameter than that illustrated.

An important feature of this invention is the provision of a machine, which is entirely self-contained and eliminates the usual overhead belt connections. Thus, the source of power may advantageously, although it need

not necessarily be, an electric motor *m*, which is fixed to the base portion of the main supporting frame, the portion *C* of the latter being made hollow for this purpose. The drive-shaft of motor *m* carries a pulley 10 and such pulley is connected by a belt 11 to a pulley 12 on a countershaft 13, which is rotatably supported from and extends along the rear side of the supporting frame. The countershaft 13 is connected through the intermediary of speed-changing devices with a second parallel countershaft 14, also mounted in the supporting frame. The speed-changing devices referred to may be of any suitable type and an example of one type is shown in Figs. 1 and 3, wherein oppositely-arranged stepped pulleys 15 and 16 on shafts 13 and 14, respectively, are connected by a belt 17. Obviously, the pulley 12 might be driven from an external source of power, if desired.

Both of the rotary spindles *J* and *T* are driven from the countershaft 14 and the tool-carrying spindle *J* is driven therefrom in the following manner. Rotatably mounted upon and along the rear side of the supporting frame and above the shaft 13, is a shaft 18 which carries an elongated pulley or drum 19 of a length coextensive with the travel of slide *H*. Shaft 18 carries a pulley 20 which is connected by a belt 21 to a pulley 22 on shaft 14. The drum 19 has belt and pulley connections to a pulley 23 on the rotary spindle *J*, but due to the cross-feeding movement of this spindle, it is necessary to interpose compensating devices to provide at all times a uniform driving connection for the spindle irrespective of its transverse travel. Such compensating devices, as illustrated, take the form of spring-actuated idler pulleys, which properly tension the driving belt at all times. For example, an arm 24 is pivoted to the supporting frame at 25 and preferably carries two idler pulleys 26, one for engagement with each lap of a belt 27 which connects the drum 19 to a pulley 28. A spring 29 connects the arm 24 to the supporting frame, and preferably in an adjustable fashion, as indicated at 30. The driving belt 27, as just described, connects with a pulley 28 rather than directly with the pulley 23. This is desirable to provide for the necessary change in direction and it also permits an increase in speed, for the pulley 28 is fixed to a larger pulley 31 which drives by a belt 32 the small pulley 23 on spindle *K*. The interposition in the driving connections of pulleys 28 and 31 also provides a conveniently adjustable tensioning means for belt 32, for these pulleys are mounted on one end of an arm 33 which is adjustably secured at its other end to the slide *K* at 34. Thus, arm 33 is angularly adjustable to vary the center to center distance

between pulleys 23 and 31 and thus adjust the tension of belt 32. The tension of belt 27 is, of course, adjustable by the device 30.

The countershaft 14 drives the spindle *T* in the following manner. On the end of shaft 14 which projects beyond the left end of the supporting frame (as viewed in Fig. 1) is fixed a stepped pulley 35 which is connected by a belt 36 to a similar pulley 37 fixed on a hollow sleeve 38 rotatably supported in the supporting frame, as shown in Fig. 6. Mounted on sleeve 38 for free rotation and held from axial movement between the pulley 37 and a collar 39 on the sleeve is a pulley 40, which is connectible with and disconnectible from pulley 37 by a suitable clutch, as will appear. Pulley 40 is connected by a belt 41 to a pulley 42 on spindle *T*. Since the latter is adapted for transverse sliding movements, it is essential to provide compensating devices to maintain a uniform driving engagement for spindle *T* irrespective of its position in its transverse travel. Such compensating devices comprise an idler pulley 43 engageable with one lap of belt 41 and mounted in one end of an arm 44, which is pivoted intermediate its ends at 45 to the supporting frame and yieldingly connected at its other end by a spring 46 (preferably adjustably as indicated at 47) to such frame.

Any suitable means may be employed for connecting and disconnecting the pulleys 37 and 40 and that particular means, shown in Figs. 6 and 7 and now to be described, is given merely for illustrative purposes. That end face of pulley 40 adjacent pulley 37 is bored out to receive a split ring 48 and radially slidable in sleeve 38 and in a collar 49 thereon is a wedge block 50, the pointed outer end of which engages between and is adapted to spread the ends of ring 48 and force it tightly against pulley 40. The band 48 is fastened at its mid point to collar 49. Thus, when the ends of band 48 are spread, the pulley 37 will drive pulley 40. The wedge-block 50 rests upon a wedge-like surface formed on a rod 51 slidable in sleeve 38. A circumferentially-grooved collar 52, fixed on the inner end of rod 51, is engaged by the forked lower end of a lever 53 which is fixed to a shaft 54 (see Fig. 1). On shaft 54 is an operating lever 55 which, when in the position shown, causes the ring 48 to expand and connect the pulleys 37 and 40. Lever 55, when swung to the right causes the disconnection of pulleys 37 and 40. The lever 55 may be operated manually, if desired, or automatically as will later appear.

It is desirable in many instances when the work *V* is moved into offset relation with the tool *I*, to disconnect the work from its driving means in order that the work may be brought to rest for inspection, meas-

urement or removal. The clutch just described permits this result, but the spindle T, which is mounted to rotate very freely, usually on antifriction bearings, will not immediately come to rest even when disconnected from its driving means. To eliminate waste time in waiting for the spindle T to come to rest, additional means are provided to automatically retard the spindle when it is moved into offset relation with the tool. Such means may be of any suitable character and as an illustrative example of one of many ways of accomplishing the desired result, reference is made to Figs. 1 and 4. Thus, a brake drum 56 may be fixed to spindle T and may, as shown, be advantageously formed as a part of the pulley 42 itself, the outer face of such pulley also being so formed to provide a hand-wheel 57, if desired. Pivoted at one end at 58 to the work head S is a substantially semi-circular brake band 59. The other end of band 59 is connected by a flexible member, as a chain 60, to one end 25 of a lever 61, and preferably there is interposed in the flexible member 60 a yieldable member, as a spring 62. The lever 61 is pivoted intermediate its ends to the slide R and, preferably, through the intermediary 30 of a bracket 63 which is connected to the slide by bolts 64, the heads of which are received in a T-slot 65 formed in slide R. The lower end of lever 61 is arranged in the path of an abutment 66 secured, preferably 35 in an adjustable fashion by means of the bracket 67 and bolt-and-slot connection 68, to the pedestal A. Thus, as slide R moves to the right (as viewed in Fig. 4) the lower end of lever 61 will eventually engage abutment 66, and continued movement of the slide will cause pressure of band 59 on drum 56. Continued movement of slide R causes increasing pressure of the band on the drum, although the tension of spring 62 may be so adjusted as to yield when the 40 braking pressure exceeds a predetermined degree. Preferably, the braking pressure is not such as to firmly hold drum 56 against rotation, for when the work is in offset relation with the tool, the operator frequently 45 wishes to turn it by hand to different angular positions. The degree of braking pressure may be also controlled by adjustment of the brackets 63 and 67, either relatively 50 to the other, and so also may the time when the braking pressure is applied.

Preferably, the disconnection of the drive for spindle T is accomplished, as by an opening of the clutch described, or otherwise slightly in advance of the application of the braking means. To insure this result, the movement of slide R, which causes the application of the braking means, may advantageously be also made to cause 55 the disconnection of the drive for spindle T.

Thus, for example, the abutment 66 serves as the pivot for a lever 69, the lower end of which is so connected to the described lever 55 as to throw the latter to the right when slide R is moved toward offset position. The upper end of lever 69 is cam-shaped and lies in the path of an abutment 70 on bracket 63. The arrangement is such that lever 69 will be engaged and moved by abutment 70 just shortly before the 75 lever 61 engages the abutment 66, the levers 61 and 69 being offset to swing without interference as indicated in Fig. 1.

The connections between the levers 55 and 69 may be of any suitable type and, as 80 an illustrative example, reference is made to Figs. 1 and 4. At that corner of pedestal A adjacent lever 69, there is pivotally mounted on a vertical axis a bell crank having two arms 71, and 72. Arm 71 is 85 connected by a link 74 (preferably adjustable for length) to the lower end of lever 69. Arm 72 is connected by a link 75 to a rocker arm 76 pivoted to pedestal A and the arm 76 is connected by a link 77 (preferably adjustable for length as indicated) to lever 55. Thus, as lever 69 is moved by abutment 70, lever 55 is swung in the right direction to open the clutch described. This clutch is of such a type that the parts, once 95 disengaged, remain in disengaged position. Thus, the member 51 and all connected parts, as levers 55 and 69, remain in the positions to which they are moved. Therefore, the upper end of lever 69, which is engaged by and moved out of the path of abutment 70, may be, but is not necessarily, engaged by the latter on a return stroke of slide R.

The rocker 76 is provided with a hole 73 in case it is desired to move slide R in the 105 opposite direction to that described and still effect the same results. In such case, link 75 would be shifted from the upper end of arm 76 to the hole 73 and lever 69 would be moved relatively to bracket 63 to the left of 110 the latter. Then on a movement of slide R to the left (Fig. 4) the clutch would be opened and the brake applied, as heretofore described.

It has been mentioned that the slide H 115 may be automatically moved and an illustrative example of one of many suitable ways, which will readily occur to those skilled in the art, for accomplishing this function is shown in Figs. 5, 8, 9, and 10. 120 Thus, the main slide H is provided with a portion a, which depends between ways G and affords a longitudinal slideway for a subslide b. The latter may be locked to the main slide, when automatic feeding of the latter is desired, by a wedge block c, which engages in a recess in sub-slide b as shown in Fig. 9. Block c is carried on the lower end of a rod d slidably mounted in slide H and yieldingly urged by a spring e toward 130

sub-slide *b*. Ordinarily, when slides *H* and *b* are moved relatively to one another the block *c* will automatically engage in the recess in sub-slide *b* and lock the two together. To prevent such action, a lever *f*, fixed to rod *d*, is provided with a cam *g* which coacts with a fixed cam *h* on slide *H*, to raise the block *c* free from sub-slide *b*.

Sub-slide *b* is connected, preferably adjustably as indicated, to one end of a connecting rod *i*, the other end of the latter being received on a crank pin *j* (Fig. 10). Such pin is carried by a slide *k* adjustable (by means of a screw, conventionally indicated at *l*) longitudinally on an arm *n*. The latter is pivoted at one end at *p* (Fig. 5) and at the other end carries a roll *r* for engagement by a cam *s*. The arrangement, thus briefly described, is a well-known one for converting rotary into reciprocating movement.

Cam *s* is fixed to a vertical shaft *t* mounted within the hollow base frame and driven by a worm gear *u* from a worm *v*. The latter is fixed to a shaft *w* which carries a pulley *x*, all as indicated in Fig. 3. Pulley *x* is driven by a belt 80 from a pulley 81 fixed to a stepped pulley 82 which is mounted for free rotation on the counter-shaft 14 described. Freely rotatable on a stud 83 on frame *C* (Fig. 5) is a double stepped pulley, one portion 84 of which is adapted for connection to pulley 82 by a belt 85 to drive the latter at various speeds. The other portion 86 is connected by a belt 87 to a stepped pulley 88 on the described shaft 13. Thus, by means of the various speed changing devices described, slide *H* may be driven at various speeds and at relatively slow speed, as desired for feeding purposes.

While it is not essential that the hand wheel *N* (used for manually feeding slide *H*) be disconnected when the automatic feed is used, it is generally desirable so to do in order to prevent the possibility of the handle (which would otherwise rotate) injuring the operator or his clothes. This is readily accomplished as shown in Fig. 11. The hand wheel *N*, which is arranged to turn the gear *O*, is loosely rotatable on a shaft 90, which in turn is rotatably mounted in a bracket 91 fixed to pedestal *B* and which is fixed to the gear *O*. A collar 92, on shaft 90, cooperates with the bracket 91 to prevent axial displacement of handwheel *N*. The latter is provided with a keyway 93 and the shaft 90 carries a slidable key 94 to engage therewith. Key 94 is fixed to a rod 95 slidable in shaft 90 and provided with a knob 96 on its outer end for convenient actuation. The key 94 extends radially through a slot 97 in shaft 90 and its outer end is freely rotatable in a counter-bore 98 in bracket 91. With the parts in

the illustrated positions, handwheel *N* is disconnected from shaft 90 and gear *O* so that rotation of the latter cannot turn the handwheel. To connect the handwheel *N* to gear *O* it is simply necessary to pull outwardly on knob 96 and turn wheel *N* until key 94 enters the keyway 93.

It is frequently desirable to provide stops for limiting or defining the limits of, travel of the tool *I* relatively to the work *V*. Generally, it is the forward stroke of the tool (the cutting stroke) which requires the stop, as the precise position of the tool at the end of its rearward stroke is generally immaterial. For example, in finishing hollow work, as by grinding the internal periphery of the hole therein, a stop to limit the inner travel of the wheel is desirable to control the depth of the hole. So also when the work is faced off, as by moving the slide *R* by means of lever *Y*, it is desirable to limit the relative movement of wheel and work to prevent, in the present case, engagement of the wheel with the jaws of chuck *U*. Many other examples of the utility of the stops will readily occur to those skilled in the art.

To limit the travel of slide *H*, a stop 100 is provided on pedestal *B* and an adjustable abutment 101 is adjustably secured to slide *H*. The engagement of these elements 100 and 101 limits the extreme outward movement of slide *H* and may be used for determining the depth of the hole to be ground. A distance piece 102 is provided, which is loosely carried by an arm 103 pivoted to a rod 104 carried by slide *H*, and this arm 103 may be swung downwardly at option, to interpose the distance piece 102 between the elements 100 and 101. The function of the distance piece is to position the slide *H* for the performance of a secondary operation, as for example, the finishing of the outer end face of the work *V*. Distance pieces of various types and lengths may also readily be substituted to effect various results.

For controlling the relative transverse positions of the tool and work, as for an end facing operation, a similar arrangement is employed, as indicated in Fig. 1, wherein 105 represents the fixed stop, 106 the adjustable abutment, 107 the distance piece, and 108 the pivoted arm. Where, as here, the end facing operation is performed by moving the work-carrying slide *R*, the stop 105 is fixed to pedestal *A* and the other elements are carried by slide *R*.

The operation of the machine will vary according to the nature of the work to be performed and, in the usual aspects, will readily be understood from the foregoing description by those skilled in the art. The operation of the unusual features of the invention, as the provision for rapidly off-

setting the work and tool for the purpose of test, inspection, assembly, or removal of work, and the provisions for retarding the rotation of the work at such a time, have 5 been explained in the foregoing description, together with the operation of the compensating devices and the auxiliary stops.

Aside from these features of the invention, a most important feature is the peculiar arrangement of parts which permits 10 a very substantial increase in working range without any increase in floor space, the advantages of which will be readily apparent to the manufacturer. I obtain these advantages by the provision of separate pedestals 15 for the work head and tool head, which permit of the pronounced depression between the two to provide the desired wide working range which permits work of widely 20 varying diameter to be handled. While obtaining the advantages described by the use of separate pedestals, I recognize the practical necessity for rigidly connecting them so that they are not independent. That is, 25 a rigid common support for the pedestals is a necessity in a grinder intended for high speed precision work. The advantages of rigidity of the work and wheel heads have been retained and yet the supporting pedestals therefor have been separated as much 30 as possible, without sacrifice to rigidity, to obtain the other important results described. The invention has been disclosed herein in a single form for illustrative purposes. It 35 is recognized, however, that many other forms and arrangements will readily suggest themselves to those skilled in the art, having for their object the use of the invention in a specific form differing from 40 that disclosed. It is, therefore, desired to have the scope of the invention determined by the appended claims interpreted by the spirit of the present disclosure rather than in the letter of the exact form disclosed.

45 What I claim is:—

1. In a grinding machine, aligned rotary work-holding and tool-holding devices, quick acting means to move one of said devices into offset relation with the other, 50 driving means for said movable devices including means associated with the driving means to maintain a uniform driving connection therewith throughout its range of movement.
2. In a grinding machine, a work head and a wheel head, a supporting frame for said heads, a rotary spindle mounted in each head, one of said heads being movable on said frame in directions parallel to and 55 at an angle with the axis of the spindle in the other head, driving means for the spindle in said movable head including compensating means movable in one direction with the movable head, whereby uniform driv-

ing force may be transmitted to the movable 65 head in any one of its various positions.

3. In a grinding machine, aligned rotary work-supporting and tool-holding devices, quick acting means to move one of said devices into offset relation with the other, 70 driving means for said movable device, and mechanism operable on such movement to connect or disconnect said driving means.

4. In a grinding machine, aligned rotary work-supporting and tool-holding devices, 75 quick acting means to move one of said devices into offset relation with the other, driving means for said movable device including means associated with the driving means to maintain a uniform driving connection therewith throughout its range of movement, and mechanism operable on such movement to connect or disconnect the driving means for said movable device.

5. In a grinding machine, a work head 80 and a wheel head, a supporting frame therefor, a rotatable spindle mounted in each head, one of said heads being movable on said frame in directions parallel to and at an angle with the axis of the spindle in the other, driving means for the spindle in the movable head mounted in said frame, said driving means including compensating means for maintaining a uniform driving connection with the movable spindle at all 85 positions in its range of travel, and means for automatically feeding the movable head in one of its directions of movement relative to the supporting frame.

6. In a grinding machine, a work head 100 and a wheel head, a supporting frame therefor, a rotatable spindle mounted in each head, one of said heads being slidable on said frame in directions substantially parallel to the axis of the spindle in the other head and also at substantially right angles thereto, driving means for the spindle in the slidable head mounted in said frame, said driving means including compensating means for maintaining a uniform driving 105 connection with the slidable spindle at all positions in its range of travel, and means for automatically feeding the slidable head in one of its directions of movement relative to the supporting frame.

7. In a grinding machine, a supporting frame, two separate slides mounted thereon for horizontal travel in different directions, a rotary spindle carried by each slide, driving means mounted in said frame, and connections from such means to each spindle including compensating means for maintaining a uniform driving connection with the spindles at all positions in their ranges of travel, and means for both manually and automatically feeding one of said slides in a horizontal direction relative to said frame.

8. In a grinding machine, a work head

- and a wheel head, a supporting frame therefor, a rotary spindle mounted in one of said heads, the last-named head being movable both longitudinally toward 5 and away from the other and in substantially transverse directions, driving means on said frame, and connections between such means and said spindle including devices to permit longitudinal and transverse movement 10 thereof and maintain at all times a uniform driving connection for the spindle, and means for automatically feeding said wheel head in one direction relative to said frame.
- 15 9. In a grinding machine, a supporting frame, a work head and a wheel head thereon and mounted for relative movement toward and away from one another, one of said heads being movable in a direction 20 transverse to the first-named movement, a rotary spindle in the last-named head, a pivoted arm movable longitudinally with the latter, idler pulleys thereon, connections between one of such pulleys and the 25 spindle, driving means for the spindle mounted in said frame, connections between the other pulley and said driving means, and a yieldingly actuated idler pulley associated with the last-named connections to 30 maintain a uniform driving connection with the spindle at all points in its transverse travel.
10. In a grinding machine, a supporting frame, a work head and a wheel head thereon and mounted for relative movement toward and away from one another, one of said heads being movable in a direction 35 transverse to the first-named movement, a rotary spindle in the last-named head, an arm pivoted to the latter, idler pulleys thereon, connections between one of such pulleys and the spindle, an elongated driving pulley mounted in the frame, connections between the latter and the other pulley on said arm, and a yieldingly actuated idler pulley associated with the last-named 40 connections to maintain a uniform driving connection with the spindle at all points in its transverse travel.
- 45 11. In a grinding machine, a supporting frame, two separate slides thereon, rotary work-supporting means on one slide and a tool-carrying spindle on the other, means for moving one slide relatively to the other, for feeding the tool longitudinally and 50 transversely relatively to the work, quick-acting means to move the other slide to bring the work and tool into off-set relation and means operable as the work and tool, the one relatively to the other, are brought toward their positions of offset relation to 55 retard the rotation of the work-supporting means.
- 60 12. In a grinding machine, a supporting frame, two separate slides thereon, rotary work-supporting means on one slide and a tool-carrying spindle on the other, means for feeding the tool longitudinally and transversely to the work, quick-acting means to move the work-carrying slide to bring the work and tool into offset relation, driving means for the work-supporting means, means to disconnect the driving and work-supporting means, and means operable as the work is moved toward its offset position 65 to retard the rotation of the work-supporting means.
13. In a grinding machine, aligned rotary work-supporting and tool-holding devices, quick-acting mechanism to move one of said devices into offset relation with the other, and mechanism operable on such movement to retard the rotation of the device thus moved.
14. In a grinding machine, aligned rotary work-supporting and tool-holding devices, quick-acting mechanism to move one of said devices into offset relation with the other, and means to disconnect and retard the 70 rotation of the said device.
15. In a grinding machine, a supporting frame, a rotary work-supporting device, a slide for the latter movable on said frame, a rotary tool-holding spindle movable longitudinally with respect to said device, slow-acting cross-feeding mechanism for said spindle, quick-acting means to move the work-supporting device into offset relation with the spindle, means operable to retard the rotation of said device as it is moved 75 into offset relation with the spindle including devices one on said slide and one on said frame and engageable on movement of the slide, and means permitting one of said devices to be moved relatively to the other.
16. In a grinding machine, a supporting frame, a rotary work-supporting device, a slide for the latter movable on said frame, a rotary tool-holding spindle movable longitudinally with respect to said device, slow-acting cross-feeding mechanism for said 80 spindle, quick-acting means to move the work-supporting device into offset relation with the spindle, means operable to retard the rotation of said device as it is moved 85 into offset relation with the spindle including devices one on said slide and one on said frame and engageable on movement of the slide, and means permitting each of said devices to be moved independently of the 90 other.
17. In a grinding machine, a supporting frame, a slide thereon, a rotary work-carrying spindle in said slide, a brake drum on such spindle, a brake band cooperating with the drum and supported on said slide, and means for applying the band to the drum 100 including a lever pivoted to said slide and

- an abutment on said frame engageable by said lever on movement of the slide.
18. In a grinding machine, a supporting frame, a slide thereon, a rotary working 5 carrying spindle in said slide, a brake drum on such spindle, a brake band cooperating with the drum and supported on said slide, and means for applying the band to the drum including a lever pivoted to said slide
- 10 and an abutment on said frame engageable by said lever on movement of the slide together with a yieldable connection between said lever and band.
19. In a grinding machine, a tool-carrying 15 spindle, rotary work supporting means, driving mechanism for the latter, quick-acting means to separate the spindle and work-supporting means to bring them into offset relation, and means operable on such separation to disconnect the work-supporting means from its driving mechanism.
20. In a grinding machine, a tool-carrying spindle, rotary work-supporting means, driving mechanism for the latter, quick-acting 25 means to separate the spindle and work supporting means to bring them into offset relation, and means operable on such separation to disconnect the work-supporting means for its driving mechanism, and apply a retarding force to the disconnected work-supporting means.
21. In a grinding machine, aligned rotary work-holding and tool-holding devices, quick acting means to move one of said devices into offset relation with the other, 35 means for moving one of said devices axially toward and away from the other, means for driving said devices including means associated with the driving means for one of said movable devices to maintain a uniform 40 driving connection therewith during its movement.
22. In a grinding machine, a work head and a wheel head, a supporting frame for said heads, a rotatable spindle mounted in 45 each head, one of said heads being movable on said frame in directions parallel to and at an angle with the axis of the spindle in the other, driving means for the spindle in the movable head comprising a drum substantially coextensive in length with the longitudinal travel of the movable head, and compensating means movable in one direction with the movable head whereby driving force may be transmitted uniformly to 55 the spindle in the movable head in any one of its various positions.

FREDERICK D. VAN NORMAN.
